UNITED STATES PATENT OFFICE.

JACQUES MORAT, OF YONKERS, NEW YORK, ASSIGNOR TO ISAAC G. JOHNSON & CO., OF NEW YORK, N. Y., A CORPORATION OF NEW YORK.

DESIGN FOR A VEHICLE-WHEEL.

44,021.

Specification for Design.

Patented May 13, 1913.

Application filed February 28, 1913. Serial No. 751,364. Term of patent 14 years.

To all whom it may concern:

Be it known that I, JACQUES MORAT, a citizen of the Republic of France, residing at Yonkers, in the county of Westchester and State of New York, have invented a new, original, and ornamental Design for Vehicle-Wheels, of which the following is a specification, reference being had to the accompanying drawing, forming part thereof.

Figure 1 is a view in perspective of the wheel, and, Fig. 2 is a sectional view trans-

versely through the rim to more clearly illustrate the design of the spokes at their point of connection with the rim.

I claim:

The ornamental design for a vehicle wheel, as shown.

JACQUES MORAT.
